UNITED STATES PATENT OFFICE.

GEORGE L. McCAIN, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,100,083.

Specification of Letters Patent. Patented June 16, 1914.

Application filed October 1, 1912. Serial No. 792,796.

To all whom it may concern:

Be it known that I, GEORGE L. McCAIN, a citizen of the United States, and resident of Detroit, Wayne county, State of Michigan, have invented certain new and useful Improvements in Hydrocarbon-Motors, of which the following is a specification.

This invention relates to hydrocarbon motors and particularly to the control mechanism therefor.

One of the objects of the present invention is to provide a hydrocarbon motor having a throttle valve and a valve controlling the oil supply, with a toggle mechanism for operating both of these valves.

Another object of the invention is to provide a hydrocarbon motor having a governor and a toggle connection between the governor and the throttle valve, with a toggle mechanism for operating the first toggle.

Another object of the invention is to provide a hydrocarbon motor with a double toggle mechanism for operating the throttle valve.

Other objects of the invention will appear from the following description taken in connection with the drawings which form a part of this specification, and in which:

Figure 1 is a side elevation of a hydrocarbon motor with some parts cut away; and Fig. 2 is a view similar to Fig. 1 with the throttle control mechanism in a different position.

Referring to the drawings, 10 represents the motor base or crank case upon which are mounted the cylinder castings 11. The intake header is shown at 12 and the intake pipe at 13. A throttle valve 14 is suitably arranged in the intake pipe to control the passage of gas to the motor. Shown as mounted upon the intake pipe 13 is a governor 15 which is of the diaphragm type. The flexible diaphragm is shown at 16 and it will be understood that the water pressure acting upon one side of the diaphragm in opposition to atmospheric pressure on the other, tends to move the diaphragm to the right or to the left as the pressure rises and falls. The water pressure is regulated entirely by the speed of the motor, as the water passing through the governor is delivered by a pump geared directly to the motor.

At the rear end of the motor base is mounted a valve 17 which is suitably held

in closed position by means of a spring 18. This valve controls the motor oiling system, being arranged between the supply pipes 17^a and 17^b, the former receiving oil from the motor driven pump 17^c and the latter delivering it to the cylinder walls through branch pipes 17^d. Thus the valve 17 regulates the supply of oil to the motor.

Keyed to the throttle valve 14 is a plate or arm 19, which arm forms one of the links of a toggle mechanism connecting the throttle with the governor 15. The other link of this mechanism is shown at 20. An operating rod 21 is also connected to the arm or plate 19 for operating the throttle in opposition to the governor, as will be clearly seen upon reference to the drawings.

The operating rod 21 is adapted to be placed under the control of the operator either through a hand controlled mechanism connected to the rod through springs 22 and a lever 23, or by a foot control device in the form of an accelerator pedal 24. The springs 22 are arranged between sliding collars 25 on the rod 21 and a stationary abutment 26 and an adjustable abutment 27, also on the rod 21. It will be seen that there is only a yielding connection between the hand controlled lever 23 and the rod 21. The rear end of the operating rod 21 is connected to an arm 28 on a rock shaft 29 mounted at the rear end of the motor, and another arm 30 of the rock shaft 29 is pivotally connected to a link 31 which in turn is connected to a pivoted lever 32 thus forming a toggle mechanism actuated by the accelerator pedal 24. The rock shaft 29 is also provided with a third arm 33 which travels in the path of the shank 34 of the oil valve 17 so that the latter may be opened as the rock shaft 29 is rocked forwardly.

It will be understood that because of the fact that the motor is usually running slowly when the throttle valve is closed, the governor is at that time operating with the least resistance to pressure on the rod 21, and at that time also, the spring 18 of the valve 17 is not pressing against the arm 33. But when the throttle valve is wide open or approximately so, the motor is usually running fast and the pressure is therefore greatest in the governor 15 and the governor is offering its greatest resistance to pressure on the rod 21, the governor of course tending to close the throttle valve.

At this time also the arm 33 is in its most forward position and the valve 17 is wide open, hence the spring 18 is tending to press the arm 33 rearwardly. There is further tendency to close the throttle by reason of the fact that the rearward spring 22 is somewhat compressed, provided of course that the hand controlled lever 23 is in the position shown in Figs. 1 and 2 of the drawings. It will be obvious that these various tendencies to move the operating rod 21 rearwardly are communicated to the accelerator pedal 24 through the rock shaft 29 and the link 31, but it will be seen upon reference to Fig. 2, that the toggle mechanism 31-32 is at this time approximately at the point of its greatest leverage, the toggle being very nearly closed, and the same is true also of the toggle connection between the governor and the throttle valve 14. Under the circumstances, it is comparatively an easy matter for the operator to hold down the accelerator pedal 24, but upon his release thereof, the governor operates immediately to close or partially close the throttle and restore the rod and connections to the position in which they are shown in Fig. 1.

Other forms of the invention than that shown may be used without departing from the spirit or scope of the invention and the specification and claims are intended to cover such modifications.

Having thus described my invention, what I claim and desire to secure by Letters Patent is:—

1. In a hydrocarbon motor, the combination with the intake pipe and the throttle valve therein, of a governor, toggle lever connections between the governor and said valve, a second toggle, means by which said second toggle may be operated, and connections between said second toggle and said valve.
2. In a hydrocarbon motor, the combination with the intake pipe and the throttle valve therein, of a governor, toggle lever

connections between the governor and said valve, a lever adapted to be controlled by the operator, a toggle operated by said lever, and connections between said latter toggle and said valve.

3. In a hydrocarbon motor, the combination with the intake pipe and the throttle valve therein, of a governor, a toggle between said governor and said valve, and a second toggle adapted to operate the first toggle.

4. In a hydrocarbon motor, the combination with the intake pipe and the throttle valve therein, of an operating rod for said valve, and a toggle mechanism for actuating said operating rod.

5. In a hydrocarbon motor, the combination with the intake pipe and the throttle valve therein, of a valve for regulating the oil supply of the motor, and a toggle mechanism for operating both of said valves.

6. In a hydrocarbon motor, the combination with the intake pipe and the throttle valve therein, of a valve for regulating the oil supply of the motor, a rock shaft, an arm on said rock shaft for operating said oil valve, a toggle mechanism controlled by the operator for rocking said shaft, and connections from said rock shaft to operate said throttle valve.

7. In a hydrocarbon motor, the combination with the intake pipe and the throttle valve therein, of a valve for regulating the oil supply of the motor, a toggle connection from the governor to the throttle valve, and a second toggle mechanism controlled by the operator and having connections with both of said valves, both of said toggles reaching approximately their greatest leverage when both valves are open.

In testimony whereof I affix my signature in the presence of two witnesses.

GEORGE L. McCAIN.
